UNITED STATES PATENT OFFICE

ALBERT BOUWERS, OF EINDHOVEN, NETHERLANDS, ASSIGNOR TO N. V. PHILIPS' GLOEILAMPENFABRIEKEN, OF EINDHOVEN, NETHERLANDS

X-RAY TUBE

Application filed February 12, 1928, Serial No. 87,795, and in the Netherlands April 6, 1925.

This invention relates to X-ray tubes the outer wall of which consists partly of metal and in which the cathode and the anticathode are surrounded for the greater part by the 5 said metal part, and has for its object to intercept within the tube the rays which do not contribute to the cone of active X-rays, so as to safeguard the operator of the tube.

According to the invention one or more 10 screens are arranged within the tube whereby the X-rays are prevented from leaving the tube through parts of the glass wall not designed for this purpose.

The metal wall of the tube may be electrically 15 connected to the anticathode; preferably, however, the anticathode is insulated from the metal part of the outer wall in such a manner that the insulation is capable of resisting the operating voltage to be supplied 20 between the earth and the anticathode. The invention may be applied for example, to X-ray tubes as described in application, Ser. No. 673,166, filed November 6, 1923 and patented as Patent 1,626,465, April 26, 1927 said tubes 25 being provided with an incandescent cathode which is brought up to substantially the same potential as that of the outer wall. The invention may also be advantageously applied to X-ray tubes as described in my application, Ser. No. 5,108, filed January 27, 1925 in which tubes the cathode and the anticathode 30 are insulated from the metal part of the outer wall, said insulations together being capable of resisting the operating voltage occurring 35 between the cathode and anticathode.

In an embodiment of the invention, a cathode is surrounded by a metal vessel which is insulated from the metal part of the wall of the tube, and which during the operation of 40 the tube, is given the same potential as or a slightly differing potential from that of the cathode, the metal screen being secured in the said vessel behind the cathode. According to the invention this metal screen may serve at 45 the same time as a support for the cathode.

Moreover, if the presence of a screen behind the cathode is not in itself sufficient to intercept all the rays that are not active, an annular metal screen may be secured to the 50 outer wall of the vessel surrounding the cath-

ode. In this case the said annular screen has to be arranged in such a manner as to intercept the non-active X-rays emanating from the anticathode and penetrating through the free space between the vessel surrounding the 55 cathode and the metal part of the outer wall.

The metal screen serving to intercept X-rays, must consist of a material which it is difficult for these rays to penetrate. Also, it is advisable to make the screen of a highly refractory material seeing that by heat conduction or by heat radiation it is frequently heated to a high temperature. Very favourable 60 results are obtained with a screen consisting of tungsten. 65

The invention will be more clearly understood with reference to the accompanying drawings in which:

Figure 1 represents an X-ray tube comprising an incandescent cathode supported 70 by a screen for intercepting the undesired rays, said screen being in direct contact with the metal part of the wall of the tube.

Figure 2 represents an X-ray tube in which an incandescent cathode is surrounded by a metal vessel which is insulated from the metal part of the outer wall and to which is secured a metal screen arranged behind the incandescent cathode in addition to an annular metal screen being arranged around the said vessel. 80

Figure 3 represents an X-ray tube of a construction similar to that shewn in Figure 2, differing, however, in that the annular metal screen around the vessel surrounding the incandescent cathode is omitted, as the construction of the tube makes such a screen superfluous. 85

Figure 4 represents an embodiment of the invention in which only an annular metal screen is arranged around the vessel surrounding the incandescent cathode, the space within the vessel being left free for the passage of the cone of active X-rays. 90

To a metal part 1 of the outer wall of the X-ray tube illustrated in Figure 1 is sealed a glass part 2 which carries an anticathode 3. To the metal part 1 is also sealed a second glass part 4, having sealed in it the leading-in wires for an incandescent cathode 5. The metal part 1 of the wall may consist, for ex- 95 100

ample, of chrome iron, or in general of a material which allows of being readily sealed to glass and which does not readily transmit X-rays. In the metal part of the wall is provided a window 6 for the passage of the active X-rays.

A screen 7 for intercepting X-rays emitted by the anticathode and directed to the glass part 4 of the wall, is fixed, by welding or in any other manner, to a receiving edge of the metal part, of the wall. This screen may serve in addition as a support for the incandescent cathode, for which purpose the leading-in wires are insulatingly carried by the screen.

Figure 2 represents a construction principally similar to the X-ray tube described in specification No. 5,108 previously mentioned. In this construction a metal part 11 of the wall is sealed on one side to a glass part 13 which carries an anticathode 14 and on the other side to a glass part 15 carrying a vessel 16 in which is mounted an incandescent cathode 17, said metal part being provided with a window 12 for the passage of the cone of active X-rays. In the construction illustrated the incandescent cathode consists of a helix which on one side is secured to a leading-in wire 18 and on the other side to a metal vessel 16 to which is connected a leading-in wire 19. The vessel 16 therefore has the same potential as the incandescent cathode 17 so that the electrons emanating from this cathode, are drawn substantially towards the anode, which during the operation of the tube has a high potential.

Inside the X-ray tube is arranged a metal screen 20, preferably, of tungsten, which rests on a collar of the vessel 16. This screen serves to intercept X-rays penetrating into the vessel 16. As the screen 20 is brought up to the same potential as the vessel 16, it will also attract but few electrons emanating from the cathode so that the electrons emitted are directed to the anticathode to a still larger extent. The screen 20 also serves to support the incandescent cathode, for which purpose the leading-in wire 18 is insulatingly carried by the screen 20.

A second screen 21, likewise of tungsten, is arranged around the vessel 16 and intercepts the X-rays emanating from the anticathode and penetrating through the space between the metal part 11 of the wall and the metal vessel 16. All the rays which might be dangerous to the operator of the X-ray tube are intercepted by the metal wall 11 and the two screens 20 and 21.

The X-ray tube illustrated in Figure 3, is substantially similar to the construction shewn in Figure 2. Similar members in this figure are referred to by the same reference numerals. This tube is provided with an incandescent cathode 25 constituted by a straight filament, one leading-in wire 18 of

which is insulatingly carried by a metal screen 20, another leading-in wire 26 being electrically connected to the said screen 20. In this construction the metal part 11 of the outer wall is constructed in such a manner that the X-rays are prevented from leaving the tube through the space between the vessel 16 and the wall 11. In this construction the annular screen 21 represented in Figure 2 is therefore superfluous.

Figure 4 represents an embodiment of the invention in which the open space within the vessel surrounding the cathode serves for the emission of the cone of active X-rays. In this figure similar members are indicated by the same reference numerals as in Figure 3. In this construction a glass part 27 sealed to a glass part 15 of the wall serves as a window. A cathode 25 carried by a metal vessel 16 is on one side electrically connected thereto whereas the other end of the cathode is secured to a leading-in wire 28 which is carried by the metal vessel 16 from which it is insulated. A tungsten screen 29 serving to intercept X-rays which would be dangerous to the operator of the tube, and which might leave the tube through the space between the vessel 16 and the part 11 of the wall, is arranged around the vessel 16 and rests on a collar of the vessel 16.

What I claim is:—

1. An X-ray tube the wall of which consists partly of metal, in which the cathode and the anticathode are surrounded for the greater part by said metal part, a metal vessel surrounding the cathode and insulated from the metal part of the wall of the tube, a screen fixed in said vessel behind the cathode, said screen being difficult for X-rays to penetrate, whereby the X-rays are prevented from leaving the tube through parts of the wall not designed for this purpose.

2. An X-ray tube the wall of which consists partly of metal, in which the cathode and the anticathode are surrounded for the greater part by said metal part, a metal vessel surrounding the cathode and insulated from the metal part of the wall of the tube, a screen fixed in said vessel behind the cathode, said screen supporting the cathode and being difficult for X-rays to penetrate, whereby the X-rays are prevented from leaving the tube through parts of the wall not designed for this purpose.

3. An X-ray tube the wall of which consists partly of metal, in which the cathode and the anticathode are surrounded for the greater part by said metal part, a metal vessel surrounding the cathode and insulated from the metal part of the wall of the tube, an annular screen secured to the outer wall of said vessel, said screen being difficult for X-rays to penetrate, whereby X-rays are prevented from leaving the tube through parts of the wall not designed for this purpose.

4. An X-ray tube the wall of which consists partly of metal, in which the cathode and the anticathode are surrounded for the greater part by said metal part, a metal vessel surrounding the cathode and insulated from the metal part of the wall of the tube, a screen fixed in said vessel behind the cathode, and an annular screen secured to the outer wall of said vessel, said screens being difficult for X-rays to penetrate, whereby X-rays are prevented from leaving the tube through parts of the wall not designed for this purpose.

10 In testimony whereof I affix my signature, at the city of Eindhoven, this 18th day of January, A. D. 1926.
